DRY PIPE SPRINKLER SYSTEM

Russell W. Gieseler, Jamestown, N. Y.

Application February 3, 1947, Serial No. 726,032

12 Claims. (Cl. 169—19)

1

This invention relates to dry pipe sprinkling systems, and more particularly to an improved dry pipe sprinkler system embodying improved features which measurably reduce the cost of installation, insures positive and reliable operation of the system, and can be conveniently maintained in good working order.

Fire protection automatic sprinkler systems generally in use are classified as either wet pipe systems or dry pipe systems. In dry pipe systems, no water is carried in the distributor pipes until one or more sprinkler heads are opened, the flow of water being sealed off at the dry pipe valve whose closure clapper is maintained in closed position by the air pressure in the distributor system. When a sprinkler head in the system opens, air in the system will escape therefrom, resulting in a reduction in air pressure within the chamber of the dry pipe valve until a point is reached where the air pressure in the dry pipe valve chamber is not sufficient to maintain the main closure clapper in closed position. Upon the opening of the main closure clapper in the chamber of the dry pipe valve, water will flow through the main water inlet port of the dry pipe valve, into the chamber thereof, thence through the distributor pipes, and through the opened sprinkler head.

To reduce pressure strain on the system, and to insure prompt flow of water through the system when a sprinkler head is open, it is desirable to maintain the air pressure in the system as low as possible. It has therefore been the practice to maintain the air pressure in the distributor system approximately $\frac{1}{2}$ of the water pressure in the main inlet port of the dry pipe valve. Dry pipe valves as presently constructed usually provide a clapper closure for sealing off the flow of water through the inlet port of the dry pipe valve, which clapper closure has an area on the air side thereof which is approximately 6 times the area of the water inlet port, so that the lower air pressure within the chamber acting against the enlarged closure area of the clapper closure will maintain the clapper closure firmly seated against the valve seat of the water inlet port, against the possibility of a sudden increase in pressure due to water surge against the water side of the clapper closure. The closure clapper also covers and seals off an intermediate air chamber which in present devices is contained within the chamber of the dry pipe valve and surrounds the water inlet valve thereof, the intermediate air chamber being in communication with the atmosphere through an alarm conduit normally containing air at atmospheric pressure and communicating with an alarm device.

2

The enlarged clapper closure commonly used, which serves as a closure for both the water inlet port and the intermediate air chamber of the dry pipe valve, is complicated in construction and expensive to manufacture and install, and due to its unwieldy size it is difficult to adjust the seating rings thereof to maintain a watertight seat between the water ring seating against the valve seat of the water inlet port, and the air ring seating against the valve seat of the intermediate air chamber. Water leaks into the intermediate chamber of the dry pipe valve, and air pressure leaks and priming water leaks from the chamber of the dry pipe valve into the intermediate air chamber, is a common occurrence.

Due to the large volume of pressure air in the distributor pipe, the opening of only one or a limited number of sprinkler heads in case of fire, would only gradually reduce the air pressure in the chamber of the dry pipe valve. In case of a fast burning fire, critical moments of time might be lost before the escaping air from the open sprinkler heads would result in a sufficient reduction of air pressure in the chamber of the dry pipe valve to cause the main clapper closure therein to swing into open position and permit inflow of water from the main inlet port thereof into the distributor pipes. It is therefore customary to provide a quick opening device which has a pipe connection to the dry pipe valve, the quick opening device being intended to rapidly reduce the differential in air pressure between the dry pipe valve chamber and the intermediate air chamber, normally under atmospheric pressure, in a manner to cause the main clapper closure to speedily fly open to permit a flow of water into the distribution system when a sprinkler head is opened.

Quick opening devices as commonly used are of two types, one type being generally known as an exhauster and the other type as an accelerator. In the exhauster type, the air pressure in the system is brought down to the tripping point by providing a discharge of air from the system through a large opening, thus exhausting the air from the system, and increasing the speed with which the pressure is reduced. The accelerator type operates to equalize the air pressure between that in the main chamber of the valve and that in the intermediate chamber, by admitting air under pressure contained within the main chamber of the dry pipe valve into the intermediate air chamber of the dry pipe valve, thus neutralizing the force directed against the air closure element by pressure in the system.

Both the exhauster type and the accelerator

type of quick opening devices as presently used, are complicated mechanisms built and constructed as separate units apart from the dry pipe valve, and connected thereto by piping. The quick opening devices presently available are inaccessible for repairs at the site, and require frequent attention and repair. The valve closures of these devices are provided with rubber closure seats which rapidly deteriorate with age and often become damaged when moved from closed to open position so that they are no longer reliable in operation. The valve closures are inaccessible for repair at the site of the installation, requiring the removal of the entire quick opening device from the system and the return of the device to the manufacturer for overhauling and repair. A standby or replacement device must then be connected into the system to insure an adequately operating sprinkler system installation.

An object of this invention is to provide an improved dry pipe automatic sprinkler system which is economical to install, may be conveniently adjusted and kept in repair, and which is positive and reliable in operation.

Another object of this invention is to provide an improved dry pipe valve assembly having incorporated into one compact unit the water flow control valve, and the quick opening device correlated with the intermediate air chamber in conduit communication with the alarm devices.

A further object of this invention is to provide an improved quick opening mechanism in operative association with the dry pipe valve of a dry pipe sprinkler system.

A still further object of this invention is to provide an improved dry pipe valve unit having an improved closure arrangement for the main water port and the intermediate air chamber thereof which is simple in design and construction and may be easily adjusted and kept in repair and which is delicately responsive to air pressure drop in the system.

Other objects of this invention will become apparent as the disclosure proceeds.

In accordance with this invention, a fully automatic dry pipe fire protection sprinkler system is provided wherein water enters the system from a main conduit which is connected to a main valve housing provided with a removable plate which provides easy access to the valves and other devices therein contained. The main chamber of the valve housing when the system is in operating condition, is partially filled with priming water, and contains a main intake check valve which operates to close off the flow of water from the main when the valve is in closed position, the valve seat being provided with an annular depression connected to the intermediate chamber of the dry pipe valve, so that seepages into the system due to leakage may be voided, and water columning thereby avoided. The intermediate chamber is connected to an alarm conduit, which in turn is provided with a ball drip valve having a small diameter drain attached thereto. Water seepages from the main check valve are drained from the system through the ball drip valve. The clapper arm of the main check valve ends in an extension to which is attached a secondary valve closure element which operates to close an opening into the intermediate chamber of the valve. Thus the area of the air seat over the intermediate chamber need not be five to six times the area of the water seat over the main conduit, as is customary in systems

heretofore in use, since the air seat is placed at a greater distance from the valve fulcrum than the water seat. Thus, if the center of the air seat is placed five to six times as far from the fulcrum as the center of the water seat, an air seat of the same size as the water seat may be used. The air seat is also completely independent of the water seat insofar as removal for repair is concerned, so that the seat may be easily and quickly removed, if necessary, by removing a hinge pin or bolt, and may be equally easily and quickly replaced. Another advantage of this type of installation is that the size of the intermediate chamber may be greatly reduced, thus insuring faster operation of a quick opening device of the accelerator type.

The main chamber of the valve housing also contains a quick opening valve clapper, having attached thereto a closure element which operates to close another opening into the intermediate chamber. This valve clapper is pivoted on a fulcrum block, and remains in closed position until released by a plunger which trips a trigger device, allowing the closure element to be opened by means of a spring attachment, or, in an alternative exemplification, the plunger presses down upon an arm of the clapper extending to the other side of the fulcrum block, thus forcing open the closure element. Upon opening of this valve closure element, the priming water in the valve housing will flow into the intermediate chamber much faster than it can escape through the alarm conduit, thus, due to its relative incompressibility, rapidly destroying the differential in pressure between that in the main chamber and that in the intermediate chamber, so that the pressure in the main water intake will force open the main check valve, allowing water to enter the system and flow to the sprinkler heads. An advantage of this arrangement is that the closure element is easily accessible for cleaning or removal through the cover plate on the valve housing.

An air chamber is provided external to the valve housing, which is divided by a diaphragm into an upper and a lower chamber, the upper chamber being connected to the lower chamber by means of a conduit containing a restricted orifice, the lower chamber being connected to the main chamber of the valve housing by means of a conduit of large diameter. A plate to which the trigger-tripping or closure-opening plunger is attached is held firmly against the lower surface of the diaphragm by means of a coil spring, the plunger passing into the main valve chamber through a bearing, contained within the conduit by means of which the lower chamber is connected to the main chamber of the valve housing, its lower end making contact with the trigger device or arm of the quick opening valve. A perforated plate is held firmly against the upper surface of the diaphragm by means of a rod, in order to prevent deformation of the diaphragm by the pressure against it of the lower plate, the perforations being provided so that air pressure in the upper chamber may act against the diaphragm.

When the system is placed in operation, the air pressures in the upper and lower chambers will be equalized in a very short time, since an air-connection between the upper and lower chambers is provided. When one or more sprinkler heads open, the air pressure in the system will drop, as will the air pressure in the lower air chamber. A sudden decrease in air pressure in the upper air chamber is prevented by the restricted orifice. The higher pressure remaining in

the upper chamber expands the diaphragm, which carries before it the plunger, thereby opening the "quick opening valve closure," and thereby allowing the priming water to flow into the intermediate chamber of the main valve housing, thus destroying the pressure differential between that in the main chamber and that in the intermediate chamber, allowing the main check valve to open.

Although the characteristic features of this invention will be particularly pointed out in the claims appended hereto, the invention itself, and the manner in which it may be carried out, may be better understood by referring to the following description taken in connection with the accompanying drawings forming a part hereof, in which

Fig. 1 is a side elevational view of the improved dry pipe sprinkler system, the building in which it is installed being diagrammatically illustrated.

Fig. 2 is a vertical cross section of the main valve assembly showing the water seat closure element and the air seat closure element in closed position, the open position thereof being illustrated by dotted lines, this section being taken on line 2—2 of Fig. 3.

Fig. 3 is a horizontal cross-section of the main valve assembly, this section being taken on line 3—3 of Fig. 2.

Fig. 4 is a vertical cross-section of the main valve assembly, this section being taken on line 4—4 of Fig. 3.

Fig. 5 is a vertical cross-section of a detail of the main valve assembly, this section being taken on line 5—5 of Fig. 3.

Fig. 6 is a vertical cross-section of the air chamber associated with the improved quick-opening device, this section being taken along the line 6—6 of Fig. 2.

Fig. 7 is a vertical cross-section of the main valve assembly in an alternative exemplification.

Fig. 8 is a horizontal cross-section of the main valve assembly, this section being taken along line 8—8 of Fig. 7, and

Fig. 9 is a vertical cross-section of a detail of the main valve assembly taken along the line 5—5 of Fig. 3, showing an alternative exemplification of the quick opening valve.

Similar reference characters refer to similar parts throughout the several views of the drawings and specification.

There is illustrated in Fig. 1 this improved dry pipe sprinkler system as it may be installed in a typical four story building, having an outside wall 10, a roof 11, and a series of floors 12. The improved sprinkler system as shown in Fig. 1 generally comprises an intake conduit 13 leading from a water main 14, and which makes connection with the valve housing 15. The conduit 13 is fitted with a gate valve 16 by means of which water may be prevented from flowing into the system when it is shut down for repairs.

From the valve housing 15 a conduit 20 leads to an alarm mechanism which may be either a water motor or a hydrostatic switch, or both. For purposes of illustration, there is shown in Fig. 1 a combination of a water motor 21 attached to an outside gong 22, and a hydrostatic switch 23 which actuates an electrical alarm 24 when tripped by water pressure in the conduit 20. The alarm conduit 20 may be provided with a ball drip valve 19 connected with a drain 18, through which water seepage into the intermediate chamber 36 of the valve may be voided. From the valve housing 15 an outlet conduit 25 connects with distribution pipes 26, to which are at-

tached sprinkler heads 27 at the various floors.

A drain 28 leads from the valve housing 15, and is fitted with a gate valve 29, so that it may be closed off and pressure maintained in the system when it is in operating condition. An air compressor 30 is also provided, which may pump air into the valve housing 15 through a conduit 31 until the desired air pressure in the system has been built up, the conduit 31 being provided with an air supply valve 32, whereby air flow into the valve housing 15 may be controlled.

The valve assembly consists of a valve housing 15 which is divided into a main chamber 35 and an intermediate chamber 36. The valve housing 15 is provided with a flange 37 connected to the main intake conduit 13, and a flange 38 connected to the outlet conduit 25. The valve housing 15 is fitted with a removable plate 39 secured by a plurality of bolts 40, thus affording easy access to the main chamber 35 for repairs and adjustments. The main chamber 35 is provided with a main intake port 41, a main outlet port 42, a drain port 43, an air intake port 44, and an outlet port 45 leading to the intermediate chamber 36. For inspection purposes, two other ports 46 and 46' are provided, located respectively at the intake port and at the outlet port, which connect with conduits 47 and 47' leading to pressure gauges 48 and 48' respectively. The intermediate chamber 36 is provided with a port 54 through which water may pass to the alarm conduit 20, which at its other end, is open to the atmosphere, thus insuring atmospheric pressure in the intermediate chamber under normal operating conditions.

The valve housing 15 is also provided with a port 49 through which priming water may be admitted to the main chamber 35 of the valve housing, which port 49 connects with a water conduit 50 leading to a priming chamber 51. The priming chamber 51 is provided with upper and lower priming chamber valves 52 and 52' respectively, and the conduit 50 is provided with a priming level test connection 53.

At the point where the main intake port 41 enters the main chamber 35 of the valve housing there is provided a valve seat 56 which is preferably of bronze or similar tough but easily machined metal. At the port 45 there is provided a similar valve seat 57. The valve seat 56 is provided with an annular groove 58 which is connected to a bleeder conduit 60 which leads to the intermediate chamber 36, so that leakage or seepage of water from the intake conduit 13 will be voided through the intermediate chamber 36. Thus water cannot enter the main chamber 35 of the valve housing 15 and cause water columning in the system.

The main valve housing 15 is provided with two hinge bolts 62 which pass through the walls of the main chamber 35 and upon which the main check valve 61 may swing; the main check valve clapper arm 63 being connected thereto by arms 64. The main check valve clapper arm 63 has pivotally attached thereto a water seat closure element 65, which is designed to fit snugly on the valve seat 56 when the valve is in closed position. The closure element 65 is secured to the clapper arm 63 by a hinge pin 66, passed through the clapper arm 63 and through a pair of spaced upstanding lugs 67 on the closure element 65, the hinge pin 66 extending through aligned apertures in the lugs 67 and the clapper arm 63.

The clapper arm 63 ends in an extension 68 to

which is attached an air seat closure element 69 designed to fit snugly against the valve seat 57 when the main check valve is closed. The air seat closure element 69 is pivotally connected to the clapper arm extension 68 whereby the closure element will adjust itself into a snug seating position with respect to the valve seat 57. This is effected by providing the closure element 69 with a pair of spaced upstanding lugs 70 and a hinge pin 71 which extends through aligned apertures in the lugs 70 and the arm extension 68. The closure element 69 is provided with a rubber ring or disc 72, which is attached thereto by means of a plurality of screws or bolts 73 in order to make a water-tight and air-tight seal in cooperation with the valve seat 57.

The arm extension 68 ends in a finger element 74. When the clapper arm is raised this finger element 74 will move out of position a pawl 75 which is pivoted between two fulcrum blocks 76 provided on the wall of the main chamber 35 of the valve housing 15. The pawl 75 is secured to the fulcrum blocks by means of a hinge pin 77. The pawl 75 is so shaped that the nose 78 thereof is free to move in an upward direction but a knee 79 is provided which abuts against the wall of the valve housing 15 so that downward motion is inhibited. Thus when the clapper arm 63 opens it cannot reseat itself, due to the fact that the finger element 74 thereof will make contact with the nose 78 of the pawl 75 during its downward motion and will be held thereby in open position, thus preventing water columning in case the clapper 63 is raised by water hammer in the main intake conduit 13.

The area of the water seat closure element 65 is determined to a very large degree by the diameter of the main intake conduit 13. The area of the air seat closure element 69, however, is determined by the distance of its center from the hinge bolts 62 as compared to the distance of the center of the water seat closure element 65 from the hinge bolts 62. In dry pipe systems it is customary to provide an air seat which is concentric with the water seat, the air seat being from five to six times the area of the water seat, the larger area being necessary in order that unnecessarily high air pressures in the system may be avoided, high air pressures tending to lengthen the time interval between the tripping of the main check valve and the arrival of water at the sprinkler heads. Such a construction results in large and unwieldy closure elements which are difficult to remove for cleaning or repair. By providing a greater leverage action on the air seat than on the water seat, the same effect may be attained by the use of a smaller air seat. Thus if the distance from the hinge point to the center of the air seat is six times the distance from the hinge point to the center of the water seat, the seats being of equal areas, the effect would be the same as if the water seat had been surrounded by a concentric air seat of six times its area, and an air pressure in the system of one sixth of the water pressure in the main will suffice to keep the main check valve in closed position.

The main chamber 35 of the valve housing 15 is also provided with a secondary port 82 leading to the intermediate chamber 36. This secondary port 82 is provided with a valve seat 83. A clapper arm 84 is pivoted on paired fulcrum blocks 85 by means of a hinge pin 86, which may be placed approximately midway of its length, as illustrated, although it may be placed at any convenient position. The clapper arm 84 is provided at one end with a closure element 87 which may be af-

fixed thereto by appropriate means and which is designed to fit securely over the valve seat 83 when the valve is in closed position. The other end of the clapper arm is so positioned above the floor of the main chamber 35 that by a downward movement thereof the closure element 87 may be raised out of contact with the valve seat 83, thus allowing a flow of air or water from the main chamber 35 to the intermediate chamber 36.

The quick opening diaphragm housing 88 is constructed from two sections of cast iron or steel thereby forming an upper housing 89 and a lower housing 90. A diaphragm 91 is placed between the upper housing 89 and the lower housing 90 and the housings are then connected by means of a plurality of bolts 92, thereby dividing the diaphragm housing 88 into upper and lower air chambers 93 and 94 respectively. The upper housing 89 is provided with a drain port 95 through which water may be voided from the upper chamber 89 and a gauge port 97 through which air may pass under pressure through a conduit 98 to a pressure gauge 99. The upper housing 89 is also provided with a port 100 containing a restricted orifice 101 which may be constructed of a circular piece of Monel or other corrosion-resistant material having a pin-hole therein. This port 100 makes connection with a conduit 102 leading to a port 103 in the lower housing 90.

A rod 105 is secured to the interior of the upper portion of the upper housing 89 by suitable means such as screw threads 106. A plate 107 is secured to the lower end of the rod 105 in such a position that it will make contact with the diaphragm 91 but exert no pressure thereon. The plate 107 is provided with a plurality of perforations 108 so that air pressure in the upper chamber 93 of the quick opening diaphragm housing 88 may act upon the diaphragm 91.

The lower housing 90 is connected to the main chamber 35 of the valve housing by means of a conduit 110 which passes through a port 111 in the valve housing 15. A rod 114 passes through a bearing 113 in the floor of the lower housing 90, and thence through the conduit 110 into the main chamber 35 of the valve housing 15, its lower end making contact with the free end of the clapper arm 84. A plurality of ports 112 lead from the lower air chamber 94 to the interior of the conduit 110, assuring an unrestricted passage of air between the main chamber 35 and the lower air chamber 94. The rod 114 is provided at its upper extremity with a plate 115 and is secured thereto by suitable means such as screw threads 116. A coil spring 117 which is compressed between the plate 115 and the floor of the lower housing 90 serves to hold the plate 115 in firm contact with the diaphragm 94.

An alternative exemplification of the new and improved quick opening valve is shown in Fig. 9. In this exemplification the port 82 leading from the main chamber 35 of the valve housing 15 to the intermediate chamber 36 thereof is closed by a closure element 125 which is attached by suitable means to a clapper arm 126 which is pivotally hung in fulcrum blocks 127 by means of a hinge pin 128. The clapper arm 126 has an arm extension 129 attached thereto. A coil spring 130 is compressed between the arm 129 and the floor of the main chamber 35 when the valve is in closed position, the clapper being held in closed position by means of a trigger device 131. The trigger device 131 is pivotally secured to the floor of the main chamber 35 by means of fulcrum blocks 132 and a hinge pin

133. The trigger device 131 is provided with a neck 134 which fits over the end of the arm extension 129 of the clapper arm 126 thus holding it firmly in closed position. The trigger device 131 is also provided with an arm 135. The arm 135 cooperates with the lower end of the rod 114, so that downward motion of the rod 114 will cause the trigger device 131 to rock upon the hinge pin 133, thus disengaging the neck 134 from the arm extension 129. When the neck 134 is disengaged by downward motion of the rod 114 and arm 135, the spring 130 acting upon the arm extension 129 will force the closure element 125 to unseat itself, thereby causing a flow of priming water into the intermediate chamber 36.

When the system is placed in operation, the main chamber 35 of the valve housing 15 is filled with priming water to a depth sufficient to cover all the valves to a depth of 2 to 3 inches, and the air pressure in the system is brought up to the desired level by means of the air pump 30. This pressure should be considerably more than is necessary to maintain the main check valve closed under normal pressure conditions in the main water intake conduit 13, since water hammer may momentarily raise the pressure in the intake conduit 13 to a considerable extent. For instance, where water pressure in the main is sixty pounds per square inch and the ratio of area of air seat to water seat is six to one, it is customary to maintain thirty-five pounds of air pressure in the system as compared to the minimum of ten pounds actually needed. Air will enter the lower air chamber 94 of the quick opening diaphragm housing 88 through the conduit 110 and the ports 112 and will enter the upper chamber 94 of the quick opening diaphragm housing 88 through the conduit 102 and the restricted orifice 101. It will be appreciated that the air pressure in the upper chamber 93 will not build up as rapidly as the air pressure in the lower chamber 94 due to the fact that it must enter the upper chamber 93 through the restricted orifice 101. However in a very short time the air pressure in the upper chamber 93 and the lower chamber 94 will be equal. The air pressure in the main chamber 35 of the valve housing 15 acting against the valve closure elements 69 and 87 will keep firmly closed the ports 45 and 82 to the intermediate chamber 36 which, being open to the outside atmosphere through the conduit 20, remains at atmospheric pressure. Thus the water tight integrity and air tight integrity of the system is assured.

Gate valve 16 is now opened so that in case of fire a flow of water from the main 14 through the main intake conduit 13 is provided.

In the event of the opening of a sprinkler head 27 in the system, due to fire or mechanical defects, the air pressure in the system would drop rapidly due to the escape of air through the sprinkler head 27. The pressure in the lower chamber 94 of the quick opening diaphragm housing 88 will likewise drop rapidly since it is connected to the system by means of the large orifice ports 112 and the conduit 110. The pressure in the upper chamber 93 of the quick opening diaphragm housing 88 will not drop as rapidly, however, due to the fact that the air in the upper chamber 93 must escape through the restricted orifice 101. Thus the air pressure in the upper chamber 93 acting upon the diaphragm 91 through the perforations 108 will depress the diaphragm 91 carrying before it the

plate 115 and the rod 114. In the exemplification illustrated in Fig. 5 the rod 114 will press down upon the arm 88 of the clapper 84 thereby raising the valve closure element 87 and allowing the priming water to flow into the intermediate chamber 36. Water will enter the intermediate chamber 36 faster than it can exit therefrom through the alarm conduit 20, and will build up a pressure in the intermediate chamber 36, destroying the differential in pressure existing between that in the intermediate chamber 36 and that in the main chamber 35. The pressure of water in the main intake 41 acting against the valve closure element 65 will then be sufficient to force the clapper arm 63 upward, allowing water to enter the system and flow through to the sprinkler heads.

In the exemplification illustrated in Fig. 9 the rod 114 when forced down by the action of air pressure against the diaphragm 94 will force down the arm 135 of the trigger device 131, disengaging the neck 134 in contact with the arm extension 129 of the clapper 126. The action of the coil spring 130 against the arm extension 129 will raise the closure element 125 from its position on the valve seat 83 thereby allowing water to flow into the intermediate chamber 86, thus destroying the differential in pressure existing between that in the main chamber 35 and in the intermediate chamber 36 of the valve housing 15, and permitting the opening of the main check valve.

When the intermediate chamber 36 is filled with water, due to the opening of either the quick opening closure element 87 or the air seat closure element 69, water will flow therefrom through the alarm conduit 20 to the alarm devices 21 and 23, thereby causing an alarm to be sounded.

When the main check valve opens, as illustrated in Fig. 2, it will be observed that the main check valve arm 61 will swing out of the way of the intake port 41 so that no frictional resistance is offered to the passage of water from port 41 to the chamber 31 in the valve housing 15.

As illustrated in Figs. 7 and 8, the new and improved quick opening device may also be applied to valves in which the air seat is concentric with the water seat. Fig. 7 illustrates such a valve having a main intake port 140 which is provided with a valve seat 141 preferably made of bronze or some other easily machined metal. An annular depression 142 surrounds the valve seat 141 thereby forming an intermediate chamber, which is connected with the alarm conduit 20 by means of a passage 143. A valve seat 144 is provided about the outer periphery of the annular depression 142, the area enclosed by the valve seat 144 being six to seven times the area enclosed by the valve seat 141. A main check valve 145 is provided, the clapper arm 146 of which is hung upon hinge pins 147 secured to the wall of the valve housing 15. A closure element 147' is attached to the clapper arm 146 by suitable means such as a hinge pin 148' passing through lugs 149 on the upper surface of the closure element 147', and through the clapper arm 146. The closure element 147' is provided with a bronze ring 150 designed to seat securely against the valve seat 141 and with a rubber ring 151 which is designed to seat securely against the valve seat 144, the rubber ring 151 being secured to the closure element 147' by means of a plurality of bolts 152.

A quick opening arm 155 is provided which has attached thereto a closure element 156 de-

11

signed to fit securely against a valve seat 157 in a port 158 which is connected with the intermediate chamber 142 by passage 148, as shown in Fig. 7. The quick opening valve may be of either the designs referred to above and is operated by the rod 114 in the same manner as described above.

When the quick opening valve 155 is opened by the action of the rod 114 the priming water will flow through the port 158 into the passage 148 and thence into the intermediate chamber 142 thereby destroying the pressure differential existing between the main chamber 35 and the intermediate chamber 142. Pressure in the main intake port 140 will then force open the main check valve 145 allowing a free flow of water therethrough into the system and through the system to the sprinkler heads 27. Water will also flow from the intermediate chamber 142 through the passage 148 and the alarm conduit 20 and to the alarm devices 21 into 23, operating the said devices to sound an alarm.

This improved quick opening device is simple and sturdy in construction with a minimum of parts requiring attention and is easy to keep in repair. The quick opening valve seat is readily accessible for cleaning and the closure element thereof may be easily replaced in case of damage thereto.

The differential check valve illustrated in Figs. 2 and 3 has an air seat which is likewise readily accessible for cleaning and may be easily removed for repair. It is small in size and low in cost and may make use of standard closure elements now on the market such as the Fairbanks or Crane discs. It closes an opening to an intermediate chamber of minimum size, thus providing for faster action of the quick opening device.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a dry pipe water distribution and sprinkler head system supplied by a primary outlet conduit which in turn is supplied by a main intake conduit including in combination, a valve unit including a housing containing a main chamber having a main inlet port in the lower section thereof in communication with said main intake conduit and an outlet port in the upper section thereof in communication with said primary outlet conduit, an intermediate air chamber in the lower section of said main chamber open to the atmosphere, said intermediate chamber having a valve port surrounding said main valve port, a valve closure assembly including a hingedly mounted clapper arm having a main closure designed to normally close said main valve port and an intermediate closure designed to normally close said intermediate valve port, a third valve port in the lower section of said main chamber in communication with said intermediate chamber, a quick opening closure for said third valve port, a port leading into said housing for admitting priming water into the lower half section of said main chamber, means for establishing a water blanket in the lower section of said main chamber of predetermined depth overlying said main closure, intermediate closure and quick opening closure when said closures are in valve closing position, means for injecting air under pressure into said main chamber above the water blanket,

12

and means responsive to a pressure drop in the upper section of said main chamber for controlling the opening movement of said quick opening closure to thereby admit priming water from the lower half section of said main chamber into said intermediate chamber and substantially concurrently cause said intermediate closure to move into open position.

2. In a dry pipe water distribution and sprinkler head system supplied by a primary outlet conduit which in turn is supplied by a main intake conduit including in combination, a valve unit including a housing containing a main chamber having a main inlet port in the lower section thereof in communication with said main intake conduit and an outlet port in the upper section thereof in communication with said primary outlet conduit, an intermediate air chamber in the lower section of said main chamber open to the atmosphere, said intermediate chamber having a valve port in the lower section of said main chamber whose center is linearly spaced from the center of said main valve port, a valve closure assembly including a clapper arm hinged at one side of said main valve port and having a main closure closing said main valve port and an intermediate closure secured to said clapper arm in spaced relation to said main closure for closing said intermediate valve port, a third valve port in the lower section of said main chamber in communication with said intermediate chamber, a quick opening closure for said third valve port, a port leading into said housing for admitting priming water into the lower half section of said main chamber, means for establishing a water blanket in the lower section of said main chamber of predetermined depth overlying said main closure, intermediate closure and quick opening closure when said closures are in valve closing position, means for injecting air under pressure into said main chamber above the water blanket, and means responsive to a pressure drop in the upper section of said main chamber for controlling the opening movement of said quick opening closure to thereby admit priming water from the lower half section of said main chamber into said intermediate chamber and substantially concurrently cause said intermediate closure to move into open position.

3. An improved valve unit for dry pipe fire protection sprinkler systems including in combination, a main valve housing having a main chamber, a main water inlet port leading into the lower section of said main chamber and a sprinkler system outlet port leading from the upper section of said main chamber, an intermediate air chamber designed to contain air at atmospheric pressure having an intermediate port communicating with the lower section of said main chamber, a quick opening port in communication with the lower section of said main chamber and said intermediate chamber, valve closures for said main inlet port, intermediate port and quick opening port contained within the lower section of said main chamber, means for admitting priming water into the lower half section of said main chamber to provide a water blanket of predetermined depth overlying said quick opening port and said intermediate port, means for admitting air under pressure into the upper section of said main chamber above the water blanket, and means responsive to a pressure drop in the upper section of said main chamber for controlling the opening movement of said quick opening closure and thereby admit priming

water from the lower half section of said main chamber into said intermediate chamber and substantially concurrently cause said intermediate closure to move into open position.

4. An improved control valve unit for dry pipe fire protection sprinkler systems including in combination, a main valve housing having a main chamber designed to contain priming water in the lower section thereof and air under pressure in the upper section thereof, a main inlet port leading into the lower section of said main chamber, an intermediate air chamber open to the atmosphere and having a port in communication with the lower section of said main chamber, a third port in the lower section of said main chamber providing communication between the lower section of said main chamber and said intermediate chamber, a main closure for said main inlet port, an intermediate closure for said intermediate port, a quick opening closure for said third port, a hinged clapper arm connected to said main closure and said intermediate closure whereby said main and intermediate closures may be simultaneously moved into open position, and means responsive to a pressure drop in the upper section of said main chamber for controlling the opening movement of said quick opening closure to thereby admit priming water from the lower section of said main chamber into said intermediate chamber and substantially concurrently cause said intermediate closure to move into open position.

5. An improved valve unit for dry pipe fire protection sprinkler systems including in combination, a main valve housing having a main chamber designed to contain priming water in the lower section thereof and air under pressure in the upper section thereof, a main inlet port leading into the lower section of said main chamber and a main outlet port leading from the upper section of said main chamber, an intermediate air chamber open to the atmosphere and having a port in communication with the lower section of said main chamber, a quick opening port within said housing providing communication between the lower section of said main chamber and said intermediate chamber, a main closure for said main inlet port, an intermediate closure for said quick opening port, a hinged clapper arm detachably connected to said main closure and said intermediate closure whereby said main and intermediate closures may be simultaneously moved into open position, a hinged clapper arm detachably connected to said quick opening closure, and a quick opening device for controlling the opening movement of said quick opening closure, said device including a rod extending into said main chamber for manipulating the hinged clapper arm and its associated quick opening closure into port opening position, and means communicating with the upper compressed air containing section of said main chamber and responsive to air pressure drop in the upper section of said main chamber for manipulating said rod.

6. An improved valve unit for dry pipe fire protection sprinkler systems including in combination, a main valve housing having a main chamber normally designed to contain priming water in the lower section thereof and air under pressure in the upper section thereof, a main inlet port leading into the lower section of said main chamber and a main outlet port leading from the upper section of said main chamber, an intermediate air chamber open to the atmosphere and

having a port in communication with the lower section of said main chamber, a quick opening port within said housing providing communication between the lower section of said main chamber and said intermediate chamber, a main closure for said main inlet port, an intermediate closure for said intermediate port, a quick opening closure for said quick opening port, a hinged clapper arm connected to said main closure and said intermediate closure whereby said main and intermediate closures may be simultaneously moved into open position, and a quick opening device for controlling the opening movement of said quick opening closure, said device including

5 a resilient element normally urging said quick opening closure into open position, a trigger element normally retaining said quick opening closure in closed position against the opening action of said resilient element, and means responsive to air pressure drop in the upper section of said main chamber for tripping said trigger element.

7. A control valve unit for dry pipe sprinkler systems including in combination, a main valve housing having a main chamber designed to contain priming water in the lower section thereof and air under pressure in the upper section thereof, a main water inlet port leading into the lower section of said main chamber and a primary outlet port leading from the upper section of said main chamber, an intermediate chamber designed to contain air under atmospheric pressure having a port in communication with the lower section of said main chamber, said intermediate port having its center lineally spaced from the center of said main inlet port, a closure for each of said ports, a clapper arm hinged adjacent to said main inlet port and detachably connected to said lineally spaced main valve closure and intermediate valve closure, and means responsive to a pressure drop in the upper section of said main chamber for controlling the opening movement of said intermediate closure.

8. A control valve unit for dry pipe sprinkler systems including in combination, a main valve housing having a main chamber designed to contain priming water in the lower section thereof and air under pressure in the upper section thereof, a main water inlet port leading into the lower section of said main chamber and a primary outlet port leading from the upper section of said main chamber, an intermediate chamber designed to contain air under atmospheric pressure having a port in communication with the lower section of said main chamber, said intermediate port having its center lineally spaced from the center of said main inlet port, a quick opening port in communication with the lower section of said main chamber and said intermediate chamber, a closure for each of said ports, a clapper arm hinged adjacent to said main inlet port and connected to said lineally spaced main valve closure and intermediate closure, and means responsive to a pressure drop in the upper section of said main chamber for controlling the opening movement of said quick opening closure.

9. A control valve unit for dry pipe sprinkler systems including in combination, a main valve housing having a main chamber designed to contain priming water in the lower section thereof and air under pressure in the upper section thereof, a main water inlet port leading into the lower section of said main chamber and a primary outlet port leading from the upper section of said main chamber and a primary closure for said main inlet port, a quick opening port in communication with the lower section of said main chamber and said intermediate chamber, a closure for each of said ports, a clapper arm hinged adjacent to said main inlet port and connected to said lineally spaced main valve closure and intermediate closure, and means responsive to a pressure drop in the upper section of said main chamber for controlling the opening movement of said quick opening closure and the admission of priming water into said intermediate chamber.

70 10. A control valve unit for dry pipe sprinkler systems including in combination, a main valve housing having a main chamber designed to contain priming water in the lower section thereof and air under pressure in the upper section thereof, a main water inlet port leading into the lower section of said main chamber and a primary outlet port leading from the upper section

15

of said main chamber, an intermediate chamber designed to contain air under atmospheric pressure having a port in communication with the lower section of said main chamber, said intermediate port having its center lineally spaced from the center of said main inlet port, a quick opening port communicating with the lower section of said main chamber and said intermediate chamber, a closure for each of said ports, a clapper arm hinged adjacent to said main inlet port and detachably connected to said lineally spaced main closure and intermediate closure, resilient means for normally urging said quick opening closure into open position, tripping means for normally retaining said quick opening closure in closed position, and means responsive to a pressure drop in said main chamber operative to manipulate said tripping means to permit said quick opening closure to move into open position and admit priming water from the lower section of said main chamber into said intermediate chamber.

10. A control valve unit for dry pipe sprinkler systems including in combination, a main valve housing having a main chamber designed to contain priming water in the lower section thereof and air under pressure in the upper section thereof, an intermediate chamber designed to contain air at atmospheric pressure, a port within the lower section of said main chamber leading to said intermediate chamber, a closure for said intermediate port, a diaphragm housing having a flexible diaphragm therein defining an air chamber on either side thereof, a restricted orifice connecting one of said air chambers to the other of said air chambers, said other air chamber being in air communication with the upper compressed air containing section of said main chamber, and means operatively connected to said diaphragm for controlling the opening movement of said intermediate closure and the admission of priming water into said intermediate chamber in accordance with the air pressure drop in said main chamber.

11. A control valve unit for dry pipe sprinkler systems including in combination, a main valve housing having a main chamber designed to contain priming water in the lower section thereof and air under pressure in the upper section thereof, an intermediate chamber designed to contain air at atmospheric pressure, a port within the lower section of said main chamber leading to said intermediate chamber, a closure for said intermediate port, a diaphragm housing having a flexible diaphragm therein defining an air chamber on either side thereof, a restricted orifice connecting one of said air chambers to the other of said air chambers, said other air cham-

16

ber being in air communication with the upper compressed air containing section of said main chamber, a plunger, a plate connected to one end of said plunger, and a coil spring compressed between the floor of said other air chamber and said plate retaining the said plate in bearing position against said diaphragm, the other end of said plunger being operative to control the opening movement of said closure and the admission of priming water from the lower section of said main chamber into said intermediate chamber in accordance with the air pressure drop in said main chamber.

15. A control valve unit for dry pipe sprinkler systems including in combination, a main valve housing having a main chamber designed to contain priming water in the lower section thereof and air under pressure in the upper section thereof, an intermediate chamber designed to contain air at atmospheric pressure, a port within the lower section of said main chamber leading to said intermediate chamber, a closure for said intermediate port, a diaphragm housing having a flexible diaphragm therein defining an air chamber on either side thereof, a restricted orifice connecting one of said air chambers to the other of said air chambers, said other air chamber being in air communication with the upper compressed air containing section of said main chamber, a plunger, a plate connected to one end of said plunger, and a coil spring compressed between the floor of said other air chamber and said plate whereby said plate is normally maintained in contact with said diaphragm, the other end of said plunger being operatively connected to said closure, said plunger being operated by a differential in air pressure between the air chambers in the diaphragm housing whereby a higher air pressure in said first air chamber will cause the said plunger to move said closure into port opening position and admit priming water into said intermediate chamber.
